[57] CLAIM

The ornamental design for a mobile home foundation stand, as shown and described.

DESCRIPTION

FIG. 1 is a top, front and left side perspective view of a mobile home foundation stand showing my new design and with an I-beam of a mobile home in broken lines;
FIG. 2 is a front elevational view thereof;
FIG. 3 is a left side elevational view thereof and a mirror image of the right side elevational view thereof;
FIG. 4 is a rear elevational view thereof;
FIG. 5 is a top plan view thereof; and,
FIG. 6 is a bottom plan view thereof.
